UNITED STATES PATENT OFFICE.

JAMES NORRIE, OF QUINCY, MASSACHUSETTS.

MANGLE.

1,385,703.

Specification of Letters Patent. Patented July 26, 1921.

Application filed January 4, 1921. Serial No. 434,953.

To all whom it may concern:

Be it known that I, JAMES NORRIE, a citizen of the United States, residing at Quincy, county of Norfolk, Commonwealth of Massachusetts, have invented a certain new and useful Improvement in Mangles, of which the following is a specification, reference being had therein to the accompanying drawings.

- 10 The invention relates to a new and useful improvement in mangles for use in ironing flat goods, such for instance as sheets, pillow cases, towels, etc. In devices of this character which have heretofore been made,
- 15 there have been sometimes provided an apron on which the article to be ironed is fed between two rolls. In some such devices the article with the apron is drawn through to the opposite side where it is taken out, or
- 20 sometimes the rolls have been reversed in rotation and the article is brought back again to the front side of the machine but the outer end of the apron has hung loose. In others an endless feed apron is employed
- 25 and the article is carried by the feed apron around between the two rolls and back again onto the same side from which the article is fed. By still another method the article is wound up with the apron around one of
- 30 the rolls in the ironing or mangling process, and then drawn out again by reversing the direction of rotation of the rolls. In this last type of machine the end of the feed apron on the operative or feed side of the
- 35 machine either hangs down free or rests free on a table and has no takeup for the apron on the reverse movement. One object of the present invention is to provide two rolls for the opposite ends of the apron, one of said
- 40 rolls being a feed roll from which the apron is fed to carry the article between the two mangle rolls and to wind the apron and article around one of the mangling rolls, and when the machine is reversed and the apron
- 45 is unrolled and the article is drawn back from between the mangling rolls, the said apron is automatically re-wound around the feed roll.

It has also been found that when only a single apron is employed that the article being mangled is liable to become slightly twisted or crinkled due to its not being fed straight and becomes creased or wrinkled during the operation. One object of the present invention is to provide means whereby the article is kept from wrinkling during

its passage through the mangle rolls. This feature of the invention consists of providing a second apron which is fed in such a manner as to meet the carrier apron in superposed position thereon where they pass between the mangling rolls, so that the article to be ironed will lie between an upper and a lower apron, and as both of the aprons are positively fed the article lying between them will be kept from wrinkling.

Another feature of the invention relates to the pressure rolls and the mountings for the same. Another feature of the invention relates to the driving mechanism and the mountings therefor.

The invention will be fully understood from the following description when taken in connection with the accompanying drawings, and the novel features thereof will be pointed out and clearly defined in the claims at the close of this specification.

In the drawings, Figure 1 is a front elevation of the machine embodying the invention.

Fig. 2 is a side elevation of the machine shown in Fig. 1.

Fig. 3 is a section on line 3—3 of Fig. 2.

Fig. 4 is a detail view of the winding spring connected with the takeup roll for the supplementary apron.

Referring now to the drawings, 1 and 2 represent the two side members of the frame in which the several rollers are mounted, said side members being tied together by a cross tie 3 at the top, or by any other suitable means. A feed apron 4 is wound around a core roll 5 which is provided with trunnions 6 journaled in vertically slidable bearings in the side members of the frame, as shown in the drawings; that is, the bearings consist of boxes 7, one at each end of the roll, each of which is slidably mounted in grooved ways in the side of the frame and seated upon a spring 8 which rests upon the bottom of the slot 9 in which the box 7 slides.

The said apron 4 runs from the feed roll 5 around over a guide roll 10 journaled at the outer end of the shelf 11, thence follows on the upper surface of the shelf around onto a takeup roll 12 which is provided with trunnions 13 journaled in vertically slidable bearings 14. Said bearings 14 are slidable in vertical grooves 15 in the side members 1—2 of the frame of the machine.

A friction roll 16 is interposed between

the feed roll 5 and the takeup roll 12, being provided with trunnions 17 which are journaled in a semi-circular bearing 18 in the frame at the bottom of the vertically elongated slot 15. The periphery of said friction roll 16 engages with the surface of the outside winding of the apron 4 on the rolls 5 and 12, being held in such engagement by the upward pressure of the springs 8 against the vertically movable boxes 7 in which the roll 5 is journaled.

A presser roll 19 is provided with trunnions 20 which are journaled in boxes 21, which are vertically slidable in said slot 15, 15 the periphery of said presser roll resting upon the periphery of the takeup roll 12, or when the apron is wound around the roll 12, said roll 19 will press upon the outer winding of the apron on said roll 12, as shown 20 in Fig. 2.

The boxes 21 in which the roll 19 is journaled are provided with a grooved neck portion 22 which lies between the side of the frame and the end of the roll 19, thus spacing the end of the roll somewhat from the 25 side frame. The boxes 7 in which the roll 5 is journaled are also provided with a neck portion 23, having side grooves 24, and the presser roll 16 is formed with a neck 25 having flattened sides 26 in vertical alinement with the grooves 24 and 22 respectively of the rolls 12 and 19. A yoke 27 of inverted U-shape or somewhat hairpin-shaped, and preferably made of stiff wire 30 or of a small iron rod, goes over the top of the neck 22 of the box bearing for the upper roll and the legs of said yoke extend down in the grooves of said neck, thence in the grooves of the neck 23 of the takeup 35 roll 12, thence down along the flat sides of the neck of the lower presser roll 16, and preferably down below also the lower takeup roll 5. The lower ends of the legs of said yoke are tied together by a crosshead 28. 40 Any suitable means for connecting the lower ends of said yoke with the crosshead 28 may be employed, the means shown being to provide the lower ends of the said legs with screw threads and to provide clamp 45 nuts 29 on said legs on the upper side of said crosshead, and nuts 30 on the lower side of said crosshead so that the said crosshead may be securely connected with the legs of said yoke. The said nuts will prevent 50 the crosshead from movement, either up or down, on the yoke.

A spring 31 is secured to said crosshead 28 between the legs of the yoke, the lower end of said spring being made fast to a stationary portion of the frame in any suitable way. 55 As shown in the drawings the lower end of the spring passes through an ear 32 projecting from the frame, and has a screw-threaded nut on which is screwed a nut 33 60 on the under side of said ear 32, and the

upper end of the spring passes through the crosshead and is clamped by nuts 34-35 to secure it in the same manner that the legs of the yoke are secured to said crosshead. Said spring is under tension and tends to 70 pull the crosshead and the yoke downward, thus holding the upper end of the yoke by an elastic pressure firmly down against the neck 22 of the bearing of the upper roll 19. This in turn exerts a downward elastic pressure 75 upon the takeup roll 12 or upon the outer winding of the apron 4 on said roll. Inasmuch as said roll 12 is mounted in vertically slideable bearings, the pressure is also transmitted to the friction roll 16. As the 80 said friction roll 16 has a rigid bottom stop by reason of its trunnions 17 being seated in the bottom of the groove 18 at the lower end of the slot 15 in which the two upper rolls are mounted, there is always a friction 85 between the three upper rolls 19, 12 and 16. The lower roll 5 also has an upward elastic pressure against the friction roll 16 by reason of the upward pressure of the spring 8.

An apron 36 is made fast at one end to a tubular shaft 37 and is wound around said shaft 37, the other end of said apron being made fast to the roll 12 and being adapted to wind around the same. The two aprons, 36 and 4, both meet and become super-imposed upon each other where they pass between the two rolls 16 and 12. The article which is to be mangled will be fed onto the surface of the apron 4 where the apron passes over the shelf 11 and will be carried 100 by the apron 4 into the throat or passageway between the two rolls 12, 16. The two aprons together with the article embraced between them will be wound up around the roll 12.

A coiled spring 38 is inclosed within the tubular sleeve 37, Fig. 4, one end of said spring being made fast at 39 to a rod 40 which passes through said sleeve, the other end of said spring being made fast to the 110 sleeve 37 at 41. The said rod 40 is formed with a square head 42 which is engaged in a square socket in the bracket 43 of said sleeve, so that the rod will be kept from rotating while the sleeve 37 rotates something 115 after the manner of a spring shade roller, but the construction differs somewhat from a spring shade roller, as will be later explained. Said spring has its coils arranged in such manner that when the apron 36 is 120 being wound up around the roll 12, the said spring will be wound up to greater tension. The ordinary spring shade roller is provided with a ratchet and pawl to prevent backward rotation of the shade roller, except when the pawl is released. In this device there is no ratchet and pawl provided, so that the spring always has a tendency 125 to rotate the sleeve 37 backward, and therefore to wind up again the apron onto 130

said sleeve or roller. It is normally prevented from yielding to this, however, by the friction created by the downward pressure of the takeup roll 12 due to the pull of 5 the spring 31 on the yoke 27. When, however, the takeup roll 12 is positively rotated backward, as will be hereinafter described, this will unwind the apron 36 from the roll 12, and the spring roller 37 will take 10 up the slack and re-wind the apron 36 on the sleeve or spring roller 37 as fast as it is released from the takeup roll 12.

Means are provided for manually rotating the roll 12. Rigidly connected with the box 15 14 of the roll 12 is a bracket 44 which extends horizontally on the outer side of the side frame 1, and the outer end of the trunnion 13 projects beyond the outer face of the box 14, and is journaled in said bracket 20 44. The bracket 44 is vertically slidable with said roll 12, being slidable on the outer face of the side member 1 of the frame. A spur gear 45 is mounted fast on the outer end of said trunnion 13, and the pinion 46 25 is mounted on a stud 47 projecting from said bracket 44. Said pinion 46 engages with said spur gear 45. A crank 48 is connected with said stud shaft 47, whereby the said pinion 46 may be manually rotated thereby 30 35 rotating the spur gear 45. By reason of the gear 45 being mounted on the shaft or trunnion 13 which carries the roll 12, said roll 12 will be rotated. When the roll 12 is rotated, the upper roll 19 will also be rotated through the friction between the said roll 35 40 45 19 and the surface of the apron wound around the roll 12. The friction of the roll 16 and the apron on the roll 12 also causes the roll 16 to rotate, and in like manner the friction between the roll 16 and the apron on the lower roll 5 causes roll 5 to rotate. As the aprons are unwound from the rolls 5 and 12, the several rolls will still be maintained in frictional engagement with each other by the springs 8 and 31.

What I claim is:—

1. A mangle having two rotary rolls in frictional engagement with each other between which the article to be mangled is fed, a carrier web of sheet material on which the said article is carried during the mangling operation, said web having one end connected with one of said rolls in such manner that when the said roll is rotated in one direction the web and superposed article will be wound around the roll, and when after the winding in one direction the roll is rotated in the reverse direction, the said web and article will also be fed in the reverse direction, and a rotary takeup roll with which the other end of the web is connected and which gives out the web as the said first web-carrying roll winds up the web and which takes up the web as the said 65 first web-carrying roll unwinds the web.

2. A mangle having two rotary rolls in frictional engagement with each other between which the article to be mangled is fed, a carrier web of sheet material on which the said article is carried during the mangling 70 operation, said web having one end connected with one of said rolls in such manner that when the said roll is rotated in one direction the web and superposed article will be wound around the roll, and when after 75 the winding in one direction the roll is rotated in the reverse direction, the said web and article will also be fed in the reverse direction, a rotary take-up roll with which the other end of the web is connected and 80 which gives out the web as the said first web-carrying roll winds up the web and which takes up the web as the said first web-carrying roll unwinds the web, a guide for the web over which the web runs from 85 one of said rolls to the other, an intermediate friction roll between said two web-carrying rolls, means for maintaining said two web-carrying rolls with a yielding pressure against the intermediate roll, and means for 90 rotating said rolls.

3. A mangle having three rolls whose axes are parallel with one another, one above the other, the peripheries of the rolls being adjacent each other, a web of sheet material 95 having one end connected with the lowermost of said rolls and the other end connected with the uppermost of said rolls, said web being paid out from the lowermost of said rolls and taken up by the uppermost 100 when the rolls are rotated in one direction and taken up by the lowermost roll when they are rotated in the reverse direction, the web passing between the intermediate roll and the uppermost of said rolls. 105

4. A mangle having three rolls whose axes are parallel with one another, one above the other, the peripheries of the rolls being adjacent each other, a web of sheet material having one end connected with the lowermost of said rolls and the other end connected with the uppermost of said rolls, said web being paid out from the lowermost of said rolls and taken up by the uppermost of said three rolls when the rolls are rotated in 115 one direction and taken up by the lowermost roll when they are rotated in the reverse direction, the web passing between the intermediate roll and the uppermost of said rolls, and a guide for said web from the lower 120 roll to the entrance between the other two rolls, said web serving as a carrier for the article to be mangled between the said intermediate and upper rolls.

5. A mangle having three rolls whose axes 125 are parallel with one another, one above the other, the peripheries of the rolls being adjacent each other, a web of sheet material having one end connected with the lowermost of said rolls and the other end con- 130

nected with the uppermost of said rolls, said web being paid out from the lowermost of said three rolls and taken up by the uppermost of said three rolls when the rolls are 5 rotated in one direction and taken up by the lowermost roll when they are rotated in the reverse direction, the web passing between the intermediate roll and the uppermost of said rolls, a guide for said web from the 10 lower roll to the entrance between the other two rolls, said web serving as a carrier for the article to be mangled between the said intermediate and upper rolls, means for maintaining said two web-carrying rolls with 15 a yielding pressure against the said intermediate roll and means for rotating said rolls.

6. A mangle having three rolls whose axes are parallel with one another, one above the 20 other, the peripheries of the rolls being adjacent each other, a web of sheet material having one end connected with the lowermost of said rolls and the other end connected with the uppermost of said rolls, said 25 web being paid out from the lowermost of said rolls and taken up by the uppermost of said three rolls when the rolls are rotated in one direction and taken up by the lowermost of said rolls when they are rotated in 30 the reverse direction, the web passing between the intermediate roll and the uppermost of said rolls, a guide for said web from the lower roll to the entrance between the other two rolls, said web serving as a carrier for the article to be mangled between the said intermediate and upper rolls, a 35 presser roll mounted above the said upper web-carrying roll and means for causing said last roll to exert a yielding pressure 40 against said upper web-carrying roll, thereby pressing the said upper web-carrying roll into frictional engagement with the said roll which is intermediate said two web-carrying rolls and means for positively rotating 45 one of said rolls and thereby rotating the other rolls by their frictional engagement with each other.

7. A mangle having two rotary rolls adjacent and parallel with each other, two webs 50 of sheet material which are fed in converging paths to pass in superposed relation to each other between said two rolls, the lower of said webs carrying the article to be mangled so that it lies between said two webs as 55 they pass between said rolls, a presser roll above the upper of said two rolls which engages with the periphery of the upper of said first two rolls, and a fourth roll yieldingly mounted below the lower of said first 60 two rolls, said fourth roll being held yieldingly in engagement with said lower of the first two rolls, one end of the web being connected with the said fourth roll and paying off the web as it is wound on to the 65 upper web-carrying roll and which takes up

the web again by reverse rotation as the web is unwound from said upper web-carrying roll.

8. A mangle having two rotary rolls adjacent and parallel with each other, two webs 70 of sheet material which are fed in converging paths to pass in superposed relation to each other between said two rolls, the lower of said webs carrying the article to be mangled so that it lies between said two webs as 75 they pass between said rolls, and a spring roller with which one end of the upper web is connected and which takes up the said web during the reverse movement of the mangle rolls for the backward feed of the 80 webs and mangled article.

9. A mangle having two rotary rolls adjacent and parallel with each other, two webs 85 of sheet material which are fed in converging paths to pass in superposed relation to each other between said two rolls, the lower of said webs carrying the article to be mangled so that it lies between said two webs as 90 they pass between said rolls, a presser roll above the upper of said two rolls which engages with the periphery of the upper of said first two rolls and a fourth roll yieldingly mounted below the lower of said first two rolls, said fourth roll being held yieldingly in engagement with said lower of the first two rolls, one end of the web being connected with the said fourth roll and paying off the web as it is wound onto the upper web-carrying roll and which takes up the 95 web again by reverse rotation as the web is unwound from said upper web-carrying roll, the three upper rolls being all journaled in vertically movable bearings, yokes which engage with the bearings of the uppermost of said rolls and tension devices which hold 100 said yokes with yielding pressure against the said uppermost bearings and thereby transmit pressure to maintain the three upper rolls respectively in yielding contact with 105 each other.

10. A mangle having two rotary rolls adjacent and parallel with each other, two webs 110 of sheet material which are fed in converging paths to pass in superposed relation to each other between said two rolls, the lower of said webs carrying the article to be mangled so that it lies between said two webs as 115 they pass between said rolls, a presser roll above the upper of said two rolls which engages with the periphery of the upper of said first two rolls, and a fourth roll yieldingly mounted below the lower of said first two rolls, said fourth roll being held yieldingly in engagement with said lower of the first two rolls, one end of the web being 120 connected with the said fourth roll and paying off the web as it is wound onto the upper web-carrying roll and which takes up the web again by reverse rotation as 125 the web is unwound from said upper web- 130

carrying roll, the three upper rolls being all journaled in vertically movable bearings, yokes which engage with the bearings of the uppermost of said rolls and tension devices which hold said yokes with yielding pressure against said uppermost bearings and thereby transmit pressure to maintain the three upper rolls respectively in yielding contact with each other, a bracket fast to the shaft of the upper web carrying roll, a gear and a pinion journaled in said bracket, said gear and pinion meshing with each other and a crank mounted on the pinion shaft whereby said pinion may be rotated and thereby through said gear actuating the said upper web-carrying roll and actuating the other rolls through frictional engagement between the several rolls. 15

In testimony whereof I affix my signature.
JAMES NORRIE.
